LEG REST

Lura Ethel Bowman, Asheville, N. C.

Application February 4, 1943, Serial No. 474,747

1 Claim. (Cl. 5—327)

The present invention relates to new and useful improvements in leg rests for the occupants of beds, particularly those suffering with paralysis, and has for its primary object to provide a device of this character which is adapted to support the legs in an upwardly inclined position in a manner to promote comfort.

Another very important object of the invention is to provide a leg rest of the aforementioned character which is adapted to be expeditiously adjusted to support the legs in different positions.

Still another very important object of the invention is to provide a leg rest of the character set forth which, when not in use, may be conveniently folded in a manner to occupy a minimum of space.

Other objects of the invention are to provide a leg rest of the character described which will be comparatively simple in construction, strong, durable, highly efficient and reliable in use, and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in side elevation, showing a leg rest constructed in accordance with the present invention in use.

Figure 2 is a top plan view of the device.

Figure 3 is a view in side elevation of the leg rest, showing the inclined platform in its highest position.

Figure 4 is a rear elevational view of the device.

Figure 5 is a front elevational view.

Figure 6 is a view in side elevation, showing the device folded.

Referring now to the drawings in detail, it will be seen that the embodiment of the invention which has been illustrated comprises a substantially flat base of suitable material which is designated generally by reference numeral 1.

The base 1 includes a pair of spaced, parallel longitudinal side bars 2 having secured transversely on their rear end portions a pair of spaced cross members 3 and 4. Mounted transversely on the forward end portions of the side bars 2 is a pair of cleats 5, the purpose of which will be presently set forth.

Mounted for swinging adjustment in a vertical plane on the base 1 is a platform of suitable material which is designated generally by reference numeral 6.

The platform 6 comprises a panel 7 having one end hingedly secured, as at 8, to the cleats 5. Mounted transversely beneath the free end portion of the panel 7 is a pair of spaced bars 9 and 10.

A pair of props 11 are provided for supporting the platform 6 in raised or operative position. The supporting props 11 are hingedly secured, as at 12, on the end portions of the inner cross member 3 of the base 1.

It is thought that the manner in which the device is used will be readily apparent from a consideration of the foregoing. To support the legs 13 of the patient in a straight, upwardly inclined position, the platform 6 is swung upwardly on its hinges 8 and the props 11 are engaged beneath the panel 7 against either of the bars 9 or 10, according to the elevation at which it is desired to support the legs. It will thus be seen that the bars 9 and 10 constitute positive stops for the supporting props 11, in addition to strengthening or reinforcing the panel 7. When the device is not in use, the supporting props 11 are swung downwardly on their hinges 12 and rest on the side bars 2 of the base 1 and the platform 6 is swung downwardly on its hinges 8, said platform resting on said props.

It is believed that the many advantages of a leg rest constructed in accordance with the present invention will be readily understood, and although a preferred embodiment of the device is as illustrated and described, it is to be understood that changes in the details of construction and in the combination and arrangement of parts may be resorted to which will fall within the scope of the invention as claimed.

What is claimed is:

A leg rest comprising a base structure including a pair of spaced, parallel side bars and further including a pair of spaced, parallel cross members mounted on one end portion of said side bars, cleats mounted transversely on the other end portions of the side bars, a leg supporting platform including a panel hingedly secured, at one end, on the cleats, bars mounted transversely beneath the free end portions of the platform at longitudinally spaced points, and props hingedly mounted on the innermost of the cross members and engageable selectively with the second-named bars beneath the panel for adjustably supporting the platform in inclined positions on the base structure.

LURA ETHEL BOWMAN.
